US00D835921S

(12) **United States Design Patent** (10) **Patent No.:** **US D835,921 S**
(45) **Date of Patent:** **** Dec. 18, 2018**

(54) **END PIECE FOR A PAPER ROLL HOLDER**

(71) Applicant: **Hans Georg Hagleitner**, Zell Am See (AT)

(72) Inventor: **Hans Georg Hagleitner**, Zell Am See (AT)

(**) Term: **15 Years**

(21) Appl. No.: **29/603,168**

(22) Filed: **May 8, 2017**

Related U.S. Application Data

(63) Continuation-in-part of application No. 35/500,276, filed on Aug. 27, 2015 (U.S. filing date under 35 U.S.C. 384), and having an international filing date of Aug. 27, 2015, now Pat. No. Des. 792,122.

(57) **CLAIM**

The ornamental design for an end piece for a paper roll holder, as shown and described.

DESCRIPTION

FIG. 1 is a perspective view of the end piece for a paper roll holder, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top elevation view thereof; and,

FIG. 7 is a bottom elevation view thereof.
